CLAIM

I claim the ornamental design for a pet water dispenser with integrated standard one gallon water jug chamber, as shown and described.

DESCRIPTION

FIG. 1 is a front, right perspective view of a pet water dispenser with integrated standard one gallon water jug chamber according to my new design, shown with the lid removed;

FIG. 2 is a front, right perspective view of the pet water dispenser with integrated standard one gallon water jug chamber, shown with the lid in place on top of the chamber;
FIG. 3 is a front view thereof;
FIG. 4 is a left side view thereof;
FIG. 5 is a right side view thereof;
FIG. 6 is a bottom view thereof;
FIG. 7 is a rear view thereof; and,
FIG. 8 is a top view thereof.

The present invention relates to a pet water dispenser with integrated chamber for a standard disposable one gallon jug. It's design is characterized by a smooth, plastic, box-shaped, tower-like chamber with an extended, bowl-like reservoir at it's forward base. The chamber and reservoir are connected by a concealed channel extending from the bottle chamber to the reservoir. The illustrative broken line showing of a water jug in FIG. 1 depicts an exemplary component which might be used in conjunction with the pet water dispenser and does not actually form part of the design claim.
